MOLD POURING APPARATUS

Pearson M. Payne, Denver, Colo.

Application August 25, 1931. Serial No. 559,322

4 Claims. (Cl. 22—79)

My invention relates to a continuous casting machine.

In the methods now in use, the metal is tapped from a melting ladle which is usually operated by hand to transfer the metal to the molds. These methods are open to many objections due to the loss of time, labor and metal caused by spilling, overflowing, misruns, and the pouring of ununiform amounts of metal in the molds, 10 leaving fins and projections on the castings. It is estimated that in the casting of grinding balls a ball recovery of sixty per cent of the metal charged into the furnace is the usual practice.

15 An important object of my invention is to obviate these difficulties by automatically pouring a predetermined amount of metal into each mold.

Another object of my invention is to provide 20 a method of controlling and regulating the amount of metal which enters each mold, thereby providing a mold pouring method of great value in the casting of such articles as pistons, grinding balls, die castings and similar articles 25 manufactured in large quantities and requiring a uniform amount of metal for each casting.

A further object of my invention is to provide 30 a highly efficient machine for continuously casting metallic articles.

Still another object of my invention is to provide means for independently pouring and molding 35 grinding balls.

Other objects and advantages of my invention will be apparent during the course of the following description.

In the accompanying drawings which form a part of this description and wherein like characters of reference denote like or corresponding parts throughout the same,

40 Figure 1 is a side elevation of my improved casting machine,

Figure 2 is a top plan view thereof,

Figure 3 is a detail sectional view of a portion of the mold pouring track,

45 Figures 4 and 5 are details of one of the mold sections, and,

Figure 6 is a detail transverse section of the measuring track.

In the drawings, wherein for the purpose of 50 illustration is shown a preferred embodiment of my invention, the numeral 10 designates a rotary mold turntable rotated by means of a variable speed electric motor 11. A friction drive 12 is interposed between the motor 11 and table 10, 55 and such a drive is selected because of the de-

sirability of accurately regulating the peripheral speed of the turntable. Other types of drives may be used, however.

A series of independent molds 13, illustrated as ball molds, are formed in separable sections 60 as shown in Figures 4 and 5, separated on the center line of the molds. Independent molds of this type are less susceptible to warping than the large molds in which many balls are cast. A refractory gate 13' may be used in the mold 65 sections if desired. These molds are arranged in spaced relation around the upper surface of the turntable adjacent the periphery thereof. For the sake of clearness in the drawings, the molds 13 have not been repeated completely 70 around the periphery of the turntable. It is to be understood, however, that in the complete machine there will be one of the molds over each of the cut away portions 19 in the turn table. The molds may be opened and closed 75 by any suitable means. In the drawings I have illustrated a cam operated mechanism for opening and closing the molds. The outer mold section is rigidly fastened to a radially disposed mold guide 14, and the inner section is slidably 80 arranged in the guide. A mold operating member 15 is secured to the inner mold section and is provided at its inner end with a pair of spaced rollers 16 which engage the inner and outer surfaces of a cam 17 stationarily arranged centrally of the turntable. The cam moves the member 15 toward and away from the axis of the turntable and consequently moves the inner mold section toward the outer section to close 85 the mold, and away from the outer section to open the mold sections. An opening 18 in the bottom of each guide registers with one of the series of cutaway portions 19 in the turntable 90 and provides a space for the casting to drop through when the sections are separated.

An arm 20 is rigidly connected to a stationary shaft 21 arranged centrally of the turntable. The outer end of the arm 20 rotatably supports the mold pouring track which comprises a flanged metallic ring 22 supported by spokes 23 the hub of which is rotatably secured to the arm 20 by means of a stub shaft 24. Within the flanged ring 22, a series of independent metal-receiving cup sections 25, shown in detail 100 in Figure 3, is removably arranged. The cup sections 25 are provided with interlocking ends to hold them in position and to prevent loss of metal. The walls of each cup slope to the opening of a centrally arranged nozzle 26 which 105 extends through an opening in the bottom of

the metal ring 22. The adjoining edges of adjacent cup sections form partitions separating the cups, and if desired, these partitions may have a concave upper surface as seen at 27 in

5 Figure 6, to allow metal to flow into the next cup rather than over the sides of the ring 22. The cup sections are made from any suitable material such as refractory material, and may be replaced at will.

10 A large sprocket wheel 28 is supported to rotate with the turntable and is connected by means of a chain or the like 29 to a smaller sprocket 30 secured to the hub of the ring 22 or to the stub shaft 24. Rotation of the turntable 10 rotates the large sprocket 28 which acts through the chain 29 to rotate the smaller sprocket 30 and turn the mold pouring track in timed relation to the turntable.

15 The turntable is rotated at the desired speed and metal flows onto the track in a continuous stream from the spout 31 of a cupola or other source of molten metal supply 32. The cups 25 measure the correct amount of metal which flows through the nozzle 26 to the gate of the mold. The spout 31 is preferably provided with a discharge nozzle 33 arranged immediately above the mold pouring track and having a relatively small opening therein. Slag escapes through the opening 34 before reaching the skimming arch. The clean metal flows under the skimming arch and out nozzle 33 to the pouring track where a predetermined portion passes into each cup, as the cups pass through the pouring zone, the amount of metal received by each cup depending upon the speed of flow of the metal, and upon the peripheral speed of the turntable, which may be varied at will. The molds can be selected to form balls or other castings of any desired size, and the speed of melting and the peripheral speed of the turntable are adjusted to apportion the correct amount of metal to the molds.

20 The discharge nozzles 26 are arranged immediately above the molds and the openings therein are smaller than the mold gates, which are preferably flared at their upper ends. There will therefore be no spilling of the metal. When a refractory mold gate such as a sand core gate shown at 13' in Figure 4 is used, no metal will freeze to the gate. The recesses in the cups 25 may be formed in any desired shape, but the opening should be at the lowest point therein, and the nozzle 26 should extend below the rim 22 to prevent contact of the metal with the metal ring.

25 The openings in the discharge nozzles 26 are relatively close together, a six inch spacing having been found to be efficient, and the molds are arranged on the turntable with their gates spaced the same distance apart as the discharge openings in the mold pouring track. If desired the cam for operating the molds may be arranged outside of the turntable to move the outer mold section, and to facilitate closer grouping of the molds on the turntable.

30 A continuous stream of metal flows into the mold-pouring track and is apportioned to the molds by the cups 25. Each mold moves through the pouring zone with its gate in registration with the discharge nozzle of one of the cups and is filled during this movement. Each cup is below the discharge nozzle for a uniform interval. During this interval only enough metal

are not filled out. All of the metal melted will go into the balls or other castings and no gates and risers will have to be remelted. The cleaning costs on the castings are very low.

35 It will be seen that my process of pouring the molds is both automatic and continuous. Regulation of the turntable may be readily effected by means of the motor 11 and the friction drive 12.

40 In place of the cupola, an electric furnace, ladle or other suitable supply of metal can be employed. In place of a turntable, any form of conveyor, such as an endless belt, could be used. If the belt moved in a straight line, a measuring track of larger diameter would be 90 used.

45 While I have shown and described the preferred embodiment of my invention it is to be understood that various changes in the size, shape and arrangement of parts may be resorted to without departing from the spirit of my invention or the scope of the subjoined claims.

50 Having thus described my invention, what I claim and desire to protect by Letters Patent is:

55 1. A continuous casting machine comprising 100 a horizontal, rotary turntable; a series of molds mounted adjacent the periphery of said turntable; means for opening said molds during a portion of their travel; means for closing said molds during another portion of their travel; a supporting member; a horizontal, circular, mold pouring track rotatably supported by said supporting member to one side of the axis of and above said turntable, said pouring track having a substantially less diameter than said turntable and positioned so that its periphery will pass over the portion of said turntable where said molds are closed; a series of metal-receiving cups carried by said pouring track, each cup being provided with an independent discharge, the spacing of said discharges corresponding to the spacing of the molds on said turntable; means for synchronizing the rotation of said pouring track with the rotation of 110 said turntable so that each discharge in the former will successively register with one of the molds on the latter; and means for delivering a stream of metal to each of said cups as they reach the registering position.

60 2. A continuous casting machine comprising: 120 a base member; a vertical shaft supported by said base member; a turntable arranged to rotate about said shaft, said shaft extending above said table; a series of molds carried mounted 130 about the periphery of said table; automatic means for opening said molds during a portion of their travel and for closing said molds during another portion of their travel; an arm extending radially outward from said shaft above 135 said table; a horizontal, circular, mold pouring track rotatably supported by said arm over said table to one side of said shaft, said pouring track having a substantially less diameter than said turntable and positioned so that its 140 periphery will pass over the portion of said turntable where said molds are closed; a series of metal-receiving cups carried by said pouring track, each cup being provided with an independent discharge, the spacing of said discharges corresponding to the spacing of the molds on said turntable; means for synchronizing the rotation of said pouring track with the rotation of said turntable so that each 145 discharge in the former will successively register 150

with one of the molds on the latter; and means for delivering a stream of metal to each of said cups as they reach the registering position.

3. In a continuous casting machine having
5 horizontally placed, rotating series of spaced
apart molds, means for pouring said molds
comprising: a horizontally placed, metallic
ring, a supporting member rotatably support-
ing said ring to one side the axis of and
10 above said molds, said ring having a lesser di-
ameter than said series of molds and arranged
to rotate at a higher speed than the latter; a
series of metal-receiving cups carried by said
ring, each cup having an independent discharge
15 through said ring; and a power transmission de-
vice connecting said ring and said series of
molds to cause said ring to rotate in synchron-
ized relation to said series of molds so that the
discharges will successively register with said
20 molds during a portion of their travel.

4. In a continuous casting machine having horizontally placed, rotating series of spaced apart molds, means for pouring said molds com-
